UNITED STATES PATENT OFFICE.

LLEWELLYN B. SHULTZ, OF ST. LOUIS, MISSOURI.

FLUE-BRUSH.

SPECIFICATION forming part of Letters Patent No. 477,074, dated June 14, 1892.

Application filed March 17, 1892. Serial No. 425,311. (No model.)

To all whom it may concern:

Be it known that I, LLEWELLYN B. SHULTZ, of St. Louis, Missouri, have made a new and useful Improvement in Flue-Brushes, of which 5 the following is a full, clear, and exact description.

The improvement relates to that class of flue-brushes in which the tufts of the brush are held in a set of staves, which unitedly 10 constitute a cylindrical head therefor. In such brushes this difficulty is experienced: Owing to said head being made in sections, as described, the tufts cannot be inserted continuously around the head. The staves are 15 perforated to receive the tufts, and as the perforations cannot occur at the joints between the staves and have to be spaced a certain distance in from the edges of the staves gaps occur in the finished brush along the lines of 20 the joints referred to. To obviate the difficulty referred to and to provide an improved flue-brush are the aims of the present improvement, which consists, partly, in so constructing and combining the staves as to cause in 25 a portion of the brush a row of tufts to come opposite the joint in another portion of the brush, partly in arranging the lines of tufts in one half of the brush opposite the spaces between the lines of tufts in the other half of 30 the brush, and partly in dividing the staves transversely to enable the portions of a stave to be relatively adjusted for the purpose described or other purposes, all substantially as is hereinafter set forth and claimed, aided by 35 the annexed drawings, making part of this specification, in which—

Figure 1 is a side elevation of one of the staves; Fig. 2, an end elevation thereof, including, in broken lines, the remaining staves 40 of the brush-head; Fig. 3, a side elevation of the improved brush, not including the tufts; Fig. 4, an end elevation of the brush; and Fig. 5, a view in side elevation showing the central portion of the brush-head, the staves being divided transversely and the lines of perforations in one end of the brush-head being respectively opposite the spaces between the lines of perforations in the opposite end of 45 the brush-head.

50 The same letters of reference denote the same parts.

The brush A is of the usual construction, saving as modified or supplemented by the improvement under consideration. B B' B² represent the staves composing the brush-head. Any desirable number of staves may be used, and they are united by means of the end pieces C C' and the bolt D and nut E in the usual manner. The staves, in place of being made with straight side edges, have 55 at each side edge an offset b and a projection b'. The offset extends, say, one half the length of the stave and the projection the other half thereof, and when the staves are assembled to form the brush-head the projection upon one stave enters the offset in the abutting stave, substantially as is represented in Fig. 3, and the perforations b² in a projection b' come opposite the joint x between the opposite ends of the abutting staves. Therefore 60 in the finished brush no gap in the tufts can occur continuously throughout the length of the brush.

The improvement is carried out more effectively when the lines of perforations in 75 one half—say the half a—of the brush come, respectively, opposite the spaces between the lines of perforations in the opposite half a' of the brush, substantially as is represented in Fig. 5. By this means the tufts F in one 80 end of the brush are caused to be arranged opposite the spaces which occur between the tufts F' in the opposite end of the brush, and the brush when viewed endwise presents the appearance exhibited in Fig. 4.

To strengthen the staves, they are preferably at the line of the offsets referred to provided with a collar or flange b⁵, substantially as is represented in Figs. 1 and 3. Said collar or flange is, as well as the offset described, shaped substantially as shown to provide a space G to facilitate the assemblage of the staves, which otherwise, from imperfect fitting of the parts, might be hindered. Fig. 5 illustrates an additional feature. The 95 staves are divided transversely into two parts b⁶ and b⁷, which are united by means of the bolts b⁸, passing through the flanges upon the staves or otherwise, substantially as shown. It is obvious that by this means the two parts 100 of the stave can be relatively arranged to cause the lines of perforations in one part of

the stave to be out of line with those in the other part of the stave.

I claim—

1. A flue-brush having its staves divided transversely and united substantially as and for the purpose described.

2. A flue-brush whose staves have offsets and projections at their side edges and having in one part of the brush-head a row of projections opposite the joint between the staves in

the opposite part of the brush-head and said staves being divided transversely and united substantially as and for the purpose described.

Witness my hand this 12th day of March, 1892.

LLEWELLYN B. SHULTZ.
